UNITED STATES PATENT OFFICE.

ALPHEUS D. LAIR, OF MEXICO, INDIANA.

CIDER-MILL.

SPECIFICATION forming part of Letters Patent No. 298,864, dated May 20, 1884.

Application filed March 19, 1884. (No model.)

To all whom it may concern:

Be it known that I, ALPHEUS D. LAIR, of Mexico, in the county of Miami and State of Indiana, have invented a new and Improved 5 Cider-Mill, of which the following is a full, clear, and exact description.

The object of my invention is to provide a new and improved cider-mill, by means of which the juice can be pressed out of a large 10 quantity of apples in a very short time, and in which the pomace and cider are automatically separated, and which mill operates very rapidly, partly filters the cider, and requires but comparatively little power.

15 The invention consists in a cider-mill constructed with two endless fabric bands or aprons passed over suitable rollers, one of which aprons receives the pomace from the grinding-mill and carries it over a series of 20 rollers, above which a reciprocating presser-plate is arranged below the shafts, carrying cams for pressing the presser-plate downward. The pomace is then carried by the aprons between two presser-rollers, and is then carried 25 off by the aprons which are beaten by a pair of beaters, to cause the pomace to drop off after the juice has been extracted.

The invention also consists in various parts and details and combinations of the same, as 30 will be fully described and set forth hereinafter.

Reference is to be had to the accompanying drawings, forming a part of this specification, in which similar letters of reference indicate 35 corresponding parts in all the figures.

Figure 1 is a longitudinal sectional elevation of my improved cider-mill. Fig. 2 is a side view of the pressure-adjusting device for the presser-rollers. Fig. 3 is a plan view of 40 the mill, parts being broken out.

The frame of the machine consists of two side pieces, A, at one upper corner of which a hopper, B, is formed, the sides and ends of which are inclined downward toward the middle. In the lower part of the hopper a transverse grinding-roller, C, is located, which is mounted on a transverse shaft, C', journaled in the standards A, and provided at one end 45 with a belt-pulley, D, and at the opposite end 50 with a pulley, D'. The length of the grind-

ing-roller is about one-fourth or one-third the width of the frame. From the grinder the pomace drops upon an endless fabric band or apron, E, which passes over a roller, F, below the hopper, under a roller, J, a short distance from the roller F, over a series of rollers, H, between two presser-rollers, G and G', around a transverse roller, F², at the opposite end of the frame, and under a roller, F', at the bottom of the frame, and in the middle of its 55 length, in the direction from that end of the machine at which the roller F is located, toward the opposite end. A like endless fabric band or apron, K, passes over a roller, L, a short distance inward from the hopper, over 60 the above-mentioned roller J, over that part of the apron or band E resting on the roller H, between the rollers G and G', over a roller, L², above the roller F², so that the outer surfaces of the two endless bands E and K will 65 be in contact with each other between the roller J and the rollers G and G'. Between the top and bottom strand of the endless band or apron E a trough, M, is arranged for catching the cider, which is provided in its bottom 70 with an outlet-pipe, M', the lower part of the said trough being directly above the roller F'. 75

The bottom presser-roller, G, is provided with a belt-pulley, N, over which and the pulley D on the shaft C a crossed belt, N', passes, 80 the pulley N being considerably larger than the pulley D. A belt, O', passes over the pulley D' on the shaft C', and over a larger pulley, O, on one end of the crank-shaft P, on the opposite end of which crank-shaft a pulley, P², 85 is mounted, over which a belt, P', passes, which also passes over a pulley, Q', on a shaft, Q, provided at its opposite end with a pulley, Q², over which and a pulley, R², on the corresponding end of a shaft, R, a belt, R', passes. 90 On the ends of the shafts H' of the rollers H pulleys H² are mounted, which are arranged in pairs, and over each pair a belt, H³, passes. The two middle adjoining shafts H' are also provided with belt-pulleys H⁴, over which a 95 belt, H⁵, passes. One of the end shafts H' is provided with a pulley, H⁶, over which a belt, S', passes, which also passes over a pulley, S, on one end of the upper presser-roller, G'. A flat press-plate, T, rests on the inner 100

surface of the bottom layer or strand of the endless apron or band, K, and is located above the rollers H and below the shafts R and Q, on which shafts R and Q cams V are mounted, 5 which are adapted to act on the said presser-plate. A connecting-bar, W, is pivoted between jaws W', projecting upward from the presser-plate T, and to the crank of the shaft P. Two transverse shafts U and U', are journaled in 10 the side boards, A, and on the same wings or knockers d are formed, the shafts U and U' being so located that the knockers d can strike the bottom strands of the bands or aprons E and K after they have left the presser-rollers 15 G and G'. A pulley, g, is mounted on one end of the shaft U', and over the same a belt, h, passes, which also passes over a pulley, k, on the shaft of the bottom presser-roller, G, and adjoining the pulley N. A crossed plate, l, 20 passes over a pulley, m, on the opposite end of the shaft U', and over a pulley, m', on the corresponding end of the upper shaft, U. The parts are thus all driven from the shaft C', which is provided with a crank-handle or with 25 a driving-pulley, or connected with any other suitable means for revolving it. It is evident that in place of the belts herein described, driving chains or ropes can be used, or gearing can also be used.

30 The upper presser-roller, G', must be pressed in the direction toward the lower presser-roller, so that the two layers of fabric E and K will be pressed against each other. To accomplish this a spring, o, is arranged over the 35 journal p, resting on the shaft of the roller G', and on the said spring the plate q rests, on which the screw r is adapted to act, by means of which the tension of the spring o can be adjusted as desired.

40 The operation is as follows: The apples are placed in the hopper B, and are ground by the roller C. The pomace passes on the endless apron or band E, which moves in the direction of the arrow a', and carries the pomace 45 in between the adjoining layers of the endless bands or aprons E and K. The presser-plate T is reciprocated and assists in carrying the pomace forward. For every revolution of the shafts R and Q the cams V act on the presser-plate and press it down, thus pressing the juice 50 from the pomace, which juice or cider collects in the trough M, and flows out through the outlet-pipe M'. The pomace is then carried by the endless bands or aprons between the 55 rollers G and G', which give it a final pressing, thereby pressing out the remaining juice or cider. The beater d on the shaft U strikes the ascending bottom parts of the endless apron or band K, thus causing the pomace 60 adhering to the same to drop off, and upon the top part of the endless band or apron E. The pomace is carried by the said band over the roller F', and as the apron or band descends it is beaten by the wing or beater d on the shaft U', causing the remaining particles 65 of the pomace to drop off.

Having thus described my invention, I claim as new and desire to secure by Letters Patent—

1. In a cider-mill, the combination, with two endless fabric aprons or bands, of a series of presser-rollers, and of a reciprocating presser-plate held above the rollers, the endless bands or aprons passing between the rollers and the presser-plate, substantially as herein shown and described. 70

2. In a cider-mill, the combination, with two endless bands or aprons passing over rollers, of a series of rollers arranged below one band, and a presser-plate arranged above the other band, so that the adjoining parts of the two bands pass between the presser-plate and the rollers, substantially as herein shown and described. 75

3. In a cider-mill, the combination, with two endless bands or aprons passing over rollers, of a series of rollers arranged below one band, and a presser-plate arranged above the other band, so that the adjoining parts of the two bands pass between the presser-plate and the rollers, and of shafts carrying arms for 85 pressing the presser-plate in the direction toward the rollers, substantially as herein shown and described. 90

4. In a cider-mill, the combination, with two endless bands or aprons, of rollers over 95 which they pass, presser-rollers held under one band, a reciprocating presser-plate held above the other band, and cams or their equivalents for pressing it in the direction toward the rollers below it, substantially as herein shown and described.

5. In a cider-mill, the combination, with two endless fabric aprons or bands, of rollers over which the bands pass, a series of rollers arranged under one band, a reciprocating 105 presser-plate arranged above the other band or apron and over the rollers, and of two presser-rollers, G and G', substantially as herein shown and described.

6. In a cider-mill, the combination, with two endless fabric bands or aprons, of a presser 110 for pressing the pomace between the said bands, and of beaters for striking the bands after they have pressed the juice from the pomace, substantially as herein shown and 115 described.

7. In a cider-mill, the combination, with two endless fabric bands or aprons, of rollers over which the bands pass, the shafts U and U', provided with wings d, and gearing or belting for revolving the said shafts to cause the wings to strike the said bands or aprons, substantially as herein shown and described. 120

8. In a cider-mill, the combination, with the grinding apparatus and two endless fabric bands or aprons passing over rollers, of the reciprocating presser-plate T, the connecting-rod W, connecting the said presser-plate with the crank-shaft, the rollers H, arranged below the presser-plate, and of the presser-rollers G and G', substantially as herein shown and described. 125

130

9. In a cider-mill, the combination, with
a hopper, B, grinding-roller C, and the end-
less bands or aprons K and E, passed over
rollers, of a reciprocating presser-plate, T, the
rollers H below the presser-plate, the shafts
R and Q, carrying cams V, for pressing the
presser-plate downward, the presser-rollers G
and G', the beater-shafts U and U', and of
means for operating all the said rollers and
parts from the shaft of the grinding-rollers C, to
substantially as herein shown and described.
